UNITED STATES PATENT OFFICE.

DAVID D. GORDON, OF CHICAGO, ILLINOIS.

ADJUSTABLE SWITCH MOUNTING.

Application filed January 31, 1925. Serial No. 5,916.

To all whom it may concern:

Be it known that I, DAVID D. GORDON, a citizen of the United States, residing at Chicago, in the county of Cook and State of Illinois, have invented certain new and useful Improvements in Adjustable Switch Mountings, of which the following is a specification.

The present invention relates to adjustable switch mountings.

The present invention is useful in connection with conduits for carrying electric wires and will be described in connection with a canopy such as is commonly provided at the point at which a conduit extends through the wall of a building or other structure. The present invention contemplates switch mechanism in which it is desirable to vary the distance from the operating mechanism of a switch to the supporting member for said switch. According to the illustrated embodiment of the present invention, a switch controlled by a pendant operating member is mounted within a canopy, said switch being mounted upon a conduit or pipe. The pendant member for controlling said switch extends through an aperture in said canopy. It is desirable to vary the radial distance between said pendant member and the conduit referred to in order to accommodate different designs of canopy, it being desirable that the pendant member should hang in a vertical position, or as nearly vertical as possible.

An object of the present invention is to provide an adjustable switch mounting means suitable for mounting within a canopy, which mounting means permits adjustment of the operating mechanism of said switch.

A further object is to provide a fitting for electric lights involving a pipe or conduit, a canopy associated therewith, and a switch controlled by a pendant operating member, which operating member is adapted to extend through an aperture in said canopy, the parts being so arranged that said switch may be readily adjusted, within limits, according to the radial distance desired between said pendant operating member and said pipe or conduit.

A further object is to provide a simple adjustable switch mounting which may be readily assembled and which may be readily inspected and repaired.

Further objects will appear as the description proceeds.

Referring to the drawings—

Figure 1 is a sectional view illustrating the pipe or conduit, a canopy therefor, and pendant controlled switching mechanism embodying the principles of the present invention;

Figure 2 is a sectional view taken along the plane indicated by the arrows 2—2 of Figure 1;

Figure 3 is a view taken in the direction of the arrow 3 of Figure 1;

Figure 4 is a sectional view taken along the plane indicated by the arrows 4—4 of Figure 3;

Figure 5 is a view similar to Figure 4 but indicating the switch operating mechanism in a position such that the radial distance between the chain and the holding pipe or conduit is decreased; and

Figure 6 is a view similar to Figure 5 but showing parts of the switching mechanism spread apart relative to one another, whereby inspection and repairs may be readily had.

Referring first to Figure 1, the numeral 10 indicates a wall, partition, or other supporting member, through which extends the pipe, conduit, or other lamp supporting member 11. The electric translating devices supported by the conduit 11 are not illustrated inasmuch as they constitute no part of the present invention. The numeral 12 indicates a canopy, which in the well known manner covers the hole in the wall 10 through which the conduit 11 extends and presents a finished appearance at the juncture of the conduit 11 with said wall 10. The canopy 12 may be provided with the collar 13, which has the set screw 14 for releasably holding the canopy 12 in place against the wall. The word "wall" in this specification is to be construed with sufficient breadth to include the ceiling of a room.

The numeral 15 indicates as a whole certain electric switching mechanism which switching mechanism controls the circuit of the wires 16—16. Said wires 16—16 may lead to the electric translating devices supported by the conduit 11 either through said conduit or in any other preferred manner. A pendant operating member 17 is provided for operating the switching mechanism 15,

the canopy 12 being provided with an aperture 18 for the passage of said operating member. Where feasible, it is desirable to have the operating member 17 naturally assume a vertical position, whereby there will be a minimum of interference between said operating member and the canopy 12. The aperture 18 may occur at varying distances from the axis of conduit 11, depending upon 5 the size of the canopy and the design thereof. In order to allow the operating member 17 to hang freely it is desirable that the radial distance between said operating member 17 and canopy 12 should be adjustable. 10 The present invention provides the adjustability referred to.

The present invention contemplates a pair of clamping members 19 and 20 adapted to have gripping engagement with the conduit 20 11. Screw bolts 21—21 hold the clamping members 19 and 20 in engagement with said conduit 11, but permit ready adjustment of said clamping members longitudinally of said conduit 11 and circumferentially of said 25 conduit.

The clamping member 20 has swedged therefrom the outstanding bracket 22, which carries the pivot 22', which also serves as a rivet for holding together parts to be 30 referred to hereinafter. The numeral 23 indicates a sleeve having an end wall 23' which end wall is rotatably secured to the bracket 22 by means of the rivet 22'. Said sleeve is cut away at a portion of its circumference diametrically spaced from the clamping member 20. Mounted within the sleeve 23, which will preferably be of metal, is an insulating sleeve 24. Within the insulating sleeve 24 is certain switching 35 mechanism indicated as a whole by the numeral 25. Part of said switching mechanism 25 includes a reel, indicated as a whole by the numeral 26. The operating member 17 is adapted to operate the reel 26 to alternately open and close the circuit of the switching mechanism 25 in response to alternate pulls upon said member 17. Rotatably supported by the bracket 22 is the guard 27, which guard has the flat portion 28 adapted 40 to ride upon the bracket 22 between said bracket 22 and the end wall 23' of the sleeve 23, being pivotally supported by the rivet 22'. Said guard 27 also includes an upstanding arcuate portion 29 adapted to 45 shield the reel 26. The metal sleeve 23 and the insulating sleeve 24 are rotatable as a unit with reference not only to the bracket 22 but to the guard 27 as well. The switching mechanism 25 is non-rotatably mounted 50 with reference to the insulating sleeve 24 and has an outstanding portion 29' adapted to be engaged by the arcuate portion 29 of the guard 27. The metal sleeve 23 is provided with lugs 30, which may be turned 55 over upon an insulating portion of the

switching mechanism 25, whereby to hold said switching mechanism 25 against axial movement with reference to the sleeves 23 and 24. The operating member 17 is movable about the axis of the rivet 22' and 60 may, consequently, have its distance from the conduit 11 varied by the simple expedient of turning the sleeve 23, guard 29 and the parts housed thereby about the axis of the rivet 22'. The operating member 17 is 65 shown as extending through a guide 31 supported by the guard 27. It will be clear from an inspection of Figures 2 and 5 that the radial distance of the guide 31 and consequently of the operating member 17 from 70 the conduit 11 may be varied, within limits, whereby said member 17 may extend vertically through the aperture 18, regardless of the distance (within limits) of said aperture 18 from the conduit 11. 75

In order that the sleeve 23 and guard 27 together with the parts housed thereby may move as a unit about the axis of the rivet 22', the arcuate portion 29 of said guard may be provided with an upstanding lug 32 80 adapted to fit within a corresponding recess in the outstanding portion 29' of the switching mechanism 25. When said switching mechanism 25 is located within the sleeves 23 and 24, said upstanding lug 32, by reason 85 of its engagement with the corresponding recess in the outstanding portion 29' of the switching mechanism 25, will cause said guard 27 and sleeve 23 to move as a unit. When, however, it is desired to move the 90 guard out of guarding relationship with the reel 26, as, for example, when any part of said reel gets out of order, it is only necessary to flex upwardly the outstanding portion 29' forming part of the switching mechanism 25 to free said plate 29' from the projection 32, whereby the guard 29 may be moved independently of the switching mechanism 25 and the sleeves 23 and 24 which house said switching mechanism. Figure 6 95 illustrates the position of the guard 29 out of its normal relationship with the plate member 29' and the switch mechanism movable therewith. 100

It will be clear that the present invention 115 provides a mechanism which may be readily applied and which is applicable to canopies of varying design. By simple adjustment the operating member 17 may hang vertically, or nearly so, regardless of the distance, within limits, of aperture 18 of canopy 12 from the axis of conduit 11. Moreover, the structure permits ready inspection and repairs in case inspection and repairs are necessary. 120

Though a preferred embodiment of the present invention has been described in detail, it will be understood that many modifications will occur to those skilled in the art. It is intended to cover all such modifica- 125 130

tions that fall within the scope of the appended claims.

What is claimed is:

1. In an electric fixture, an elongated lamp supporting member, a canopy surrounding said member, and switch mechanism mounted upon said member, said switch mechanism, including a controlling member extending through an aperture in said canopy, said switch mechanism having a portion movable in a plane normal to the axis of said supporting member, whereby the distance between said operating member and said supporting member may be varied.
2. In an electric lighting fixture, in combination, an elongated supporting member, a canopy surrounding said supporting member, switching means within said canopy, clamping means for adjustably holding said switching means upon said supporting member, said switching means including a pendant operating member extending through an aperture in said canopy, part of said switching means being rotatable about an axis displaced from the axis of said supporting member, whereby the distance of said operating member from said axis may be varied.
3. In combination, a cylindrical supporting member, a canopy surrounding said supporting member, switch mechanism mounted within said canopy, clamping means for adjustably supporting said switch mechanism upon said supporting member, said clamping means including a portion for rotatably mounting said switch mechanism along an axis displaced from the axis of said supporting member, said switch mechanism being provided with an operating member adapted to extend through an aperture in said canopy.
4. In combination, an elongated supporting member, a canopy surrounding said member, switch mechanism within said canopy, clamping means for mounting said switch mechanism upon said elongated member, said clamping means including a portion extending outwardly from said elongated member, said switch mechanism including a portion rotatably carried by said outwardly extending portion of said clamping means, and a guard member for said switch mechanism also rotatably carried by said outwardly extending portion, and readily releasable means for causing said guard and said portion to move in unison.
5. In combination, an elongated cylindrical supporting member, a canopy surrounding same, switch mechanism within said canopy, said switch mechanism including a pendant operating member, said canopy having an aperture through which said pendant member extends, and means for rotatably mounting said switch mechanism about an axis parallel with but spaced from the axis of said cylindrical member, said operating member being connected to said switch mechanism at a region displaced from the axis of rotation of said switch mechanism.
6. In combination, a cylindrical supporting member, a canopy surrounding same, clamping means upon said supporting member, said clamping means including a shelf extending outwardly in a plane normal to the axis of said cylindrical supporting member, switch mechanism within said canopy and rotatably carried by said shelf, a guard for said switch mechanism also rotatably carried by said shelf and movable independently of said switch mechanism, said switch mechanism and said guard member having interfitting parts adapted to be readily connected or disconnected for causing said switch mechanism and guard to move in unison or to permit the independent movement of either said switch mechanism or said guard, said switch mechanism being provided with an operating member connected thereto at a region displaced from the axis of rotation of said switch mechanism relative to said shelf.

Signed at Chicago, Illinois, this 29th day of January, 1925.

DAVID D. GORDON.
